LOCKING DEVICE FOR LUBRICATING CUPS.

1,412,993.

Specification of Letters Patent. Patented Apr. 18, 1922.

Application filed March 15, 1920. Serial No. 365,960.

To all whom it may concern:

Be it known that I, HAROLD BATCHELOR, a resident of Jersey City, in the county of Hudson and State of New Jersey, have invented certain new and useful Improvements in Locking Devices for Lubricating Cups, of which the following is a specification.

This invention relates to improvements in locking devices, and appertains more especially to the combination of such a device with the fixed or base member of a lubricating cup for locking a threadingly engaged cap member therewith.

One of the objects of the invention is to provide an improved construction in which the cap member of the lubricating cup may be turned to any desired position of adjustment on the fixed member, while it is frictionally held against reverse turning and readily admits of further rotation in the original direction.

Another object of the invention is the provision of a locking device of the character described which will resist reverse turning of the cap member up to the application or exertion thereon of a certain force, beyond which the locking device will reverse its action, and thereafter resist rotation of the cap in the direction it was originally turned.

30 A further object is to produce a construction in which the locking device may be carried entirely by the fixed member of the lubricating cup, and wherein the said device acts directly against the cap or rotatable member without requiring any complementary elements therebetween.

Still another object is the production of a simple, inexpensive and durable locking device, not liable to get out of order, and inconspicuous, besides being applicable to existing types of lubricating cups with a minimum of cost and effort and requiring only minor or no alterations therein.

45 A still further object is to procure a construction of the kind referred to wherein the cap member of the lubricating cup will constitute a protection for the locking device against tampering as well as shield it from injury.

50 Other objects and advantages of the invention will become apparent as the specification proceeds.

With the aforesaid objects in view, the invention consists of the novel combinations and arrangements of parts hereinafter de-

scribed in their preferred embodiments, pointed out in the subjoined claims, and illustrated on the annexed drawings, wherein like parts are designated by the same reference characters throughout the several views.

In the said drawings:

Figure I is a top plan view of the fixed member of one type of lubricating cup, showing the application thereto of a certain species of the invention;

Fig. II is a vertical section on the line II-II of Fig. I looking upwardly in the direction indicated by the arrows pertaining to the said line, the cap member of the cup being shown in position;

Fig. III is a longitudinal section on the line III-III of Fig. I viewed in the direction pointed out by the arrows appertaining to the line mentioned;

Fig. IV is a fragmentary sectional elevation of the same type of lubricating cup as before mentioned showing the application thereto of another species of the invention;

Fig. V is a perspective view of a detail pertaining to the next preceding figure.

Fig. VI is a top plan view of a third species of the invention applied to another type of lubricating cup;

Fig. VII is a vertical section on the line VII-VII of Fig. VI looking up in the direction of the arrows pertaining to the said line, the cap member of the cup being shown in position;

Fig. VIII is an underside plan view of a modified detail detached from Fig. VII;

Fig. IX is a section on the line IX-IX of Fig. VIII looking in the direction pointed out by the arrows appertaining to the line named;

Fig. X is an elevation taken from the right hand side of Fig. VIII;

Fig. XI is a top plan view of the fixed member of a third type of lubricating cup with which a fourth species of the invention is embodied;

Fig. XII is a vertical section on the line XII-XII of Fig. XI looking upwardly in the direction of the arrows pertaining to the said line, the cap member of the cup being shown also;

Fig. XIII is a longitudinal section on the line XIII-XIII of Fig. XI viewed in the direction pointed out by the arrows appertaining to the line last named;

Fig. XIV is a top plan view of the fixed member of a fourth type of lubricating cup to which a fifth species of the invention is applied;

5 Fig. XV is a vertical section on the line XV—XV of Fig. XIV looking upwardly in the direction of the arrows pertaining to the said line, the cap member of the cup being shown in position;

10 Fig. XVI is a top plan view of the fixed member of a fifth type of lubricating cup with which a sixth species of the invention is incorporated;

15 Fig. XVII is a vertical section on the line XVII—XVII of Fig. XVI looking up in the direction pointed out by the arrows appertaining to the said line, the cap member of the cup being shown in position;

20 Fig. XVIII is a top plan view of the fixed member of a sixth type of lubricating cup to which a seventh species of the invention is shown applied; and

25 Fig. XIX is a vertical section on the line XIX—XIX of Fig. XVIII looking upwardly in the direction indicated by the arrows pertaining to the line named, the cap member of the cup being shown in place.

Briefly described, the invention comprises a locking element that is preferably carried 30 by the fixed or base member of a lubricating cup, and which is wholly or in part located within the members of the latter. The locking element is composed of resilient material and comprises a stem which is mounted in a 35 socket or guide in the fixed member, or an attachment thereto. This stem has a finger thereon which is adapted to extend into contact with internal threads of the cap which screws onto the fixed member. The said 40 stem is adapted to oscillate to a limited extent in its socket. Then the end of the finger thereon describes an arc and extends somewhat beyond the periphery of the fixed member. Means are provided for predetermining 45 the movement of the stem in its socket in such a manner that the end of the finger is confined to its arc of movement which lies beyond the periphery of said fixed member and between the points of intersection of 50 said arc with said periphery. The said finger therefore contacts with the said cap when it is screwed into place and acts as a friction pawl, allowing the cap to be easily moved in one direction, but swinging toward 55 the highest part of its arc when the cap is turned in the opposite direction, hence opposing and normally preventing backward rotation of said cap. The means for limiting the oscillatory movement of the stem is 60 conveniently an arm moving between two stops or abutments on the fixed member. The construction and arrangement of the locking element is preferably such that a strong intentional twisting force applied to 65 the cap will cause the locking element to

yield and turn through its arc, whereupon it will act to check turning of the cap in a direction reverse to that in which it previously opposed rotation of the latter.

The advantages of the invention as here 70 outlined are best realized when all of its features and instrumentalities are combined in the one and same structure, but, useful devices may be produced embodying less than the whole. 75

It will be obvious to those skilled in the art to which the invention appertains, upon becoming conversant with the details thereof, that the same may be incorporated in several different constructions. The accompanying drawings, therefore, are submitted merely as showing the preferred exemplifications of the invention. 80

Referring to Figures I to III inclusive, 85 there is shown a conventional type of lubricating cup, the cylindrical portion of the fixed or base member of which is designated by the reference letter *a*, while *b* denotes exterior screw threads on the latter. The said portion *a* is joined by a tapering part *c* with a polygonal extension *d* to which a wrench may be applied when the threaded part *e* of the extension is screwed into or out of a threaded seat or orifice. A cap or rotatable member *f* of the lubricating cup, 90 having internal screw threads *g* on the cylindrical wall *h* thereof, is adapted to engage the external threads upon the fixed member and close the same. 95

To the inner face of the last mentioned 100 member *a* is attached, as by means of solder 1, a sleeve or socket-piece 2, of cylindrical or any other desired form. One end of the sleeve 2, shown as the lower end in the construction illustrated in Figures I, II and III, 105 is provided with a slot or groove 3 running transversely or radially thereof. A bore 4 passes axially or longitudinally through the sleeve 2, and receives therein a stem 7 of the locking element, the axis of this stem 110 and of the sleeve being preferably parallel with the axes of the fixed and rotatable members of the lubricating cup. One terminal of the said stem 7, as for example the upper end in Figures I, II and III, is 115 bent or offset toward the circumference of the fixed member and constitutes a finger or pawl 8 which reaches to a greater or less extent beyond the periphery of the said cylindrical portion *a*, depending on the angular position of the stem within its arc of oscillation, and is adapted to bear against the sides of the threads *g* in the cap *f*. When the finger 8 occupies a position coinciding with a radial line passing from the centre 120 of the lubricating cup to its periphery, the outer extremity of the said finger extends beyond the periphery of the portion *a*, a certain amount, or in other words, the length 125 of the finger 8 slightly exceeds the distance 130

between the bore 4 and the periphery of the said portion a , and hence its outer end swings in an arc extending beyond the said periphery.

- 5 In order to limit the turning movement of the stem 7 in its socket or guide 2, the said stem is offset at its lower extremity, as indicated at 9 in the construction shown by Figures I, II and III. This offset constitutes an arm which preferably projects in a direction opposite to that of the finger 8; that is, it is made to point toward the interior of the lubricating cup. The arm 9 projects through the slot 3, and the opposite sides 10 thereof form abutments or stops for limiting its swinging movement and consequently 15 predetermines the oscillation of the stem 7 and the therewith connected finger 8. The extreme limits of movement of the finger 8 are indicated by the dot-and-dash lines 8^x—8^y (Fig. I). Even in its extreme positions the outer point of the said finger is 20 always held in contact with the interior of the cap f .
- 25 Assuming the finger 8 to be in the position 8^y, the cap f may be screwed onto the fixed member in a clockwise direction without its rotation being opposed by the finger 8, inasmuch as the pressure of the sides of the 30 cap will be in a direction to turn the end of the said finger slightly towards the interior of the fixed member, and the sides of the cap will simply slide over the finger's free terminal. If however, the cap be turned 35 in a counter-clockwise direction, the frictional contact of the end of the finger 8 with the sides of the cap will induce the latter to move the finger around its pivotal axis in a direction to cause it to extend 40 beyond the periphery of the fixed member, and hence effect a biting or binding action of the finger against the inner face of the cap and thus prevent its reverse rotation. Notwithstanding that the semi-resilient finger 8 preferably is such as to resist 45 incidental forces tending to unscrew the cap, still its resistance may be overcome by an intentional major twisting effort in a direction to reverse the turning of the cap to 50 unscrew it. The end of the finger will then oscillate through its full arc of movement and thereafter lie at the extreme position 8^x. The cap member may then be unscrewed, as the pressure of the cap on the end of the 55 finger will again swing it inwardly or towards the interior of the fixed member, because the inner side of the cap is now in a position to slide easily over the end of the said finger 8.
- 60 By reason of the fact that the length of the finger 8 is greater than the distance from the centre of the socket 4 to the periphery of the fixed member a , it follows 65 that this finger must be forced slightly backwardly, or towards the interior of the said

fixed or base member, when made to swing past or over the before mentioned radial line extending from the centre of the lubricating cup through the said socket. This movement produces a bending action at the junction of the stem with the finger, but the flexure of the resilient material from which these parts are made takes care of the bending and twisting strains that the elements 7, 8 and 9 are subjected to.

70 Although the sleeve or socket 2 is described as being soldered to the fixed or base member a , it is obvious that it could as well be an integral part of the latter.

75 A modification of the construction shown 80 in the preceding figures, is illustrated in Figures IV and V. In the same, 2^a designates the guiding socket or sleeve for the locking element which socket is conveniently pressed from sheet metal, and provided with a slot 3^a preferably formed between two ears 12, 13, bent outwardly from the meeting edges of the sleeve.

85 In this modification, the said sleeve 2^a is attached to the fixed member in such a manner that the slot 3^a is located at the upper or open end thereof. The locking element may in the present instance be made of half round stock and have its stem bent in the middle and its ends brought close together so as to 90 be located both at the same end of the said stem. One of the ends thereof forms the finger 8^a which is bent outwardly in one direction while the other end constitutes the 95 arm 9^a that is offset oppositely, towards the 100 interior of the base a . The finger 8^a projects beyond the periphery of the latter and acts upon the cap member in the same manner as the finger 8 in the before described construction, while the sides of the arm 9^a abut 105 against the lugs 12, 13 which limit the range of oscillation of the stem 7^a and the therewith connected arm 8^a. It will be understood that the sleeve 2^a may be attached in 110 an inverted position in the construction illustrated by Figures I to III inclusive.

115 A second species of the invention is depicted in Figures VI and VII. In the contrivance here shown, the locking element is carried by a frame 2^b which is set into the fixed member a^2 without requiring any special means for holding it in place. The said frame 2^b is conveniently made of a strip of metal formed into a substantially Y-shaped structure, the strip being bent in the 120 middle, as indicated at 15, and brought together for a portion of its length, thereby producing one part of the Y, the other two portions of the latter being formed by the 125 diverging terminals of the strip marked 18 and 19. The last named portions are resilient and arranged to press outwardly against the inner walls of the fixed member a^2 to hold the frame in place therein. Two 130 opposite bends or swells 16, 17 are produced

in the two adjacent portions of the strip, and form between them a guide in which the stem 7^b of the locking element is oscillatably held. This stem has one end turned outwardly to constitute a finger pawl 8^b which is adapted to engage the inner side g^2 of the cap member f^2 in order to prevent reverse turning thereof, in the same manner as the hereinbefore described locking element shown by Figures I, II and III. Similarly, the finger 8^b permits reverse rotation of the cap f^2 when the same is intentionally turned with sufficient force to cause the said finger to yield and reverse its position with relation to the cap. The stem 7^b also has an arm 9^b projecting from its other end toward the interior of the fixed member, and this arm has an upstanding part 20 approximately parallel with the said stem, which part extends upwardly between the arms 18, 19 and is adapted to strike against the latter in order to limit the oscillation of the stem 7^b and the finger 8^b thereon.

A modified form of the invention described with reference to the views last named, is shown in Figures VIII, IX and X. In these figures, 2^c denotes the supporting frame for the locking element. The guide for receiving the stem 7^c of the latter is formed directly at the bend in the strip of metal from which this frame is made. The said stem 7^c is provided with a finger or pawl 8^c which acts against the inner part of the cap member in a manner corresponding to the previous construction. The oscillation of the stem 7^c is here limited however, by a flat faced lug 22 with which the corners of the flattened end 9^c of the said stem are adapted to come into contact.

A third species of the invention is exemplified in Figures XI, XII and XIII. The lubricating cup here represented is of a heavy type used on rough machinery. The fixed member of the cup has a shallow recess in its upper face, designated by the reference letter h , which recess is formed by an annular portion j forming the rim or upper part of the cup. The said recess h has a gap i passing across the said annular portion to the periphery of the fixed member. The opposite ends of the portion j facing the gap i constitute abutments k which serve to limit the oscillatory movement of the arm 9^d pertaining to the stem 7^d of the locking element. The said stem 7^d is guided in an opening 4^d extending through the said fixed member of the cup. The exterior end of the stem 7^d is provided with a finger or pawl 8^d, adapted to bear against the inner threaded face g^4 of the cap member f^4 of the cup and oppose unscrewing thereof, in the same manner as the corresponding parts of the previously described constructions. Moreover, by intentionally exerting a strong turning force on the cap member, the resistance of the finger

8^d may be overcome, and the said finger caused to reverse its position and its action, as heretofore explained.

A fourth species of the invention is represented in Figures XIV and XV. As herein shown the stem 7^e of the locking element is guided by an opening formed in the thick portion l of the fixed member of the cup. The said stem 7^e has a finger or pawl 8^e adapted to press against the inner threaded face g^5 of the cap f^5 and oppose unscrewing thereof, as heretofore explained in conjunction with the corresponding parts in the previously described species. The action of the finger 8^e may also be reversed as hereinbefore related. In this construction the oscillation of the stem 7^e and the therewith connected finger 8^e, is limited by the arm 9^e bent inwardly from the stem and having a downturned part 20^e which projects into a neck or extension d^5 of the fixed member of the cup. The walls of the said neck d^5 , on opposite sides act as stops against the swinging movement of the said part 20^e on the arm 9^e.

A fifth species of the invention is shown in Figures XVI and XVII. Here the fixed member of the lubricating cup has a flared or conical interior h^6 . As in preceding species, the stem 7^f of the locking element is guided in an opening in the said fixed member, and one end of the said stem is offset towards the exterior of the cup to form a finger or pawl 8^f adapted to engage the inner face of the cap member f^6 . The opposite end 9^f of the stem 7^f is bent interiorly of the cup and also downward to substantially the contour of the inside wall or face of the fixed member. As the locking element oscillates to one side or the other, the movement of the arm 9^f will be arrested by striking against opposite parts of the wall h^6 , and hence the same will limit the rocking movement of the stem and the finger or pawl 8^f thereon. The action of this locking element is similar to that of the corresponding elements in the preceding constructions.

A sixth species of the invention is illustrated in Figures XVIII and XIX. In this construction the stem 7^g of the locking element extends through and turns in a hole in the fixed member of the lubricating cup. As before, one end of this stem is bent outward to form a finger or pawl 8^g adapted to engage the inner face g^7 of the cap member f^7 in the manner and with the effect described with relation to the corresponding part in the other species. With the opposite end of the said stem is formed the arm 9^g which is lengthened towards the interior of the fixed member by a spring 25 which is preferably of the helical type and one terminal whereof is slipped over the end of the said arm as shown. The other or free end of this spring is received in a V-shaped

5 crotch *m* formed in a projection *n* upon the face of the said fixed member of the cup. When the finger or pawl is turned, this causes the spring 25 to be flexed, and the latter therefore opposes to the limit of its strength beyond the free swing thereof, the turning or oscillatory movement of stem 7^g and finger 8^g thereon.

10 It will be noticed that in the types of lubricating cups represented by Figures I to VII inclusive, the exteriorly directed finger of the locking element is located inside of both members of the cup, while in the styles of cups illustrated by Figures XI 15 to XIX the said thread engaging finger is disposed on the outside of the fixed members.

20 While certain preferred embodiments of this device have been shown and described, it will be understood that changes in the 25 form, arrangements, proportions, sizes and details thereof may be made, without departing from the scope of the invention as defined by the appended claims.

25 Having described my invention what I desire to secure by Letters Patent and claim, is:—

1. A lubricating cup or the like comprising a fixed or base member, a cap member 30 threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 35 being capable of frictionally pressing against the inner face of the cap, and other means for limiting oscillation of said stem, said limiting means consisting of an arm on the 40 stem and abutments on either side of said arm against which it is adapted to contact.

45 2. A lubricating cup or the like comprising a fixed or base member, a cap member threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 50 being capable of frictionally pressing against the inner face of the cap, and other means for limiting oscillation of said stem, the construction and arrangement being such that turning in one direction allows the cap to slide over the finger, while turning in the opposite direction causes the latter to bite or bind against said inner faces, thereby preventing accidental reverse rotation of the cap.

55 3. A lubricating cup or the like comprising a fixed or base member, a cap having screw-threaded engagement therewith, reversible means for opposing rotation of said cap relatively to said fixed member, said means consisting of a locking element including an oscillatable stem with a finger 60 projecting therefrom, the said stem being disposed in offset relation substantially parallel to the axes of the said members with the said finger projecting at approximately right angles thereto, the free end of said finger being capable of swinging in an arc outwardly beyond the periphery of the fixed member and frictionally pressing against the inner face of said cap, so that turning 65

in one direction carries the finger toward the interior of the members and allows the cap to slide over the same, but turning in the opposite direction causes the finger to bite or bind against said inner face of the 70 cap, thereby stopping accidental reverse rotation of the latter, while further intentional movement in the last named direction tends to bring the end of the finger past its outermost position beyond said periphery, where- 75 by it is reversed and enabled to either allow or oppose rotation of the cap depending upon which way it is turned, and means for limiting the oscillation of said stem.

80 3. A lubricating cup or the like comprising a fixed or base member, a cap member threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately 85 right angles thereto, the end of said finger being capable of frictionally pressing against the inner face of the cap, and other means for limiting oscillation of said stem, said limiting means consisting of an arm on the 90 stem and abutments on either side of said arm against which it is adapted to contact.

95 4. A lubricating cup or the like comprising a fixed or base member, a cap member threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 100 being capable of frictionally pressing against the inner face of the cap, means for limiting oscillation of said stem, and a socket supporting the same in proximity to the edge of the fixed member.

105 5. A lubricating cup or the like comprising a fixed or base member, a cap member threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 110 being capable of frictionally pressing against the inner face of the cap, an arm on said stem, a guide socket supporting the same and having spaced portions adapted to limit 115

the oscillatory movement of said arm and the therewith connected element.

6. A lubricating cup or the like comprising a fixed or base member, a cap member 5 threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 10 being capable of frictionally pressing against the inner face of the cap, a frame set within the fixed member supporting said stem, one end thereof constituting a contact portion, and a stop on said frame against which said portion is adapted to abut in limiting the 15 oscillation of the locking element.

20 ends of the stem.

7. A lubricating cup or the like comprising a fixed or base member, a cap member threadingly engaging the same, means for opposing rotation of said cap relatively to 25 said fixed member carried thereby, said means consisting of a locking element having an oscillatable stem with a finger extending therefrom, the said stem being disposed in offset relation substantially parallel 30 to the axes of the said members with the said finger projecting at approximately right angles thereto, the end of said finger being capable of frictionally pressing against the inner face of the cap, a frame for supporting 35 said locking element set within the fixed member, said frame having a guide for said stem, and means for limiting oscillatory movement thereof with relation to the frame.

8. A lubricating cup or the like comprising a fixed or base member, a cap member 40 threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 45 being capable of frictionally pressing against the inner face of the cap, a frame set within the fixed member supporting said stem, one end thereof constituting a contact portion, and a stop on said frame against which said portion is adapted to abut in limiting the oscillation of the locking element.

9. A lubricating cup or the like comprising a fixed or base member, a cap member 50 threadingly engaging the same, means for opposing rotation of said cap relatively to said fixed member carried thereby, said means consisting of a locking element having an oscillatable stem with a finger extending therefrom, the said stem being disposed in offset relation substantially parallel to the axes of the said members with the said finger projecting at approximately right angles thereto, the end of said finger 55 being capable of frictionally pressing against the inner face of the cap, and other means for limiting oscillation of said stem, said limiting means including an arm on the stem having a bent part at its end.

HAROLD BATCHELOR.
